RAZOR BLADE SHARPENER

William Luxmore, Chicago, Ill., assignor of one-half to Albert G. McCaleb, Evanston, Ill.

Application June 4, 1934, Serial No. 728,922

16 Claims. (Cl. 51—158)

My invention relates to razor blade sharpeners and contemplates the provision of a simple and easily manipulated mechanism which will perform a superior job of razor blade sharpening by causing each cutting edge which is to be sharpened to travel between a pair of opposed honing surfaces with which such edge alternately has sliding contact during the movement of the blade.

In its more preferred embodiments, my invention comprises two spaced-apart pairs of elongated honing surfaces, the honing surfaces of each pair defining a channel adapted to receive one of the cutting edges of a blade which is supported and reciprocated and otherwise moved between said pairs of honing surfaces, and between the honing surfaces of each pair, so that each cutting edge alternately has sliding contact, preferably in a line parallel to said cutting edge, with the honing surfaces of the pair between which that particular edge moves.

Other salient features of the invention are novel devices (a) for supporting and reciprocating a blade, (b) for moving each blade edge, by and during reciprocation, into and out of contact with the honing surfaces which act upon such edge, and (c) for insuring that the blade edges bear against their proper honing surfaces with a predetermined proper pressure regardless of the force which is utilized in reciprocating the blade to be sharpened.

Other features, objects and advantages of my invention will appear from the following description wherein reference is made to the accompanying drawings, in which

Fig. 1 is a top plan view of a preferred embodiment of my invention, the cover, with which the device may be provided, being removed;

Fig. 2 is a longitudinal section taken in the vertical plane of the line 2—2 of Fig. 1 and looking in the direction indicated by the arrows, the cover being illustrated in this figure;

Fig. 3 is a transverse section taken in the vertical plane of the line 3—3 of Fig. 2 and looking in the direction indicated by the arrows;

Figs. 4, 5 and 6 are views which respectively illustrate the blade carriage support, the blade carriage, and the blade holder,—these three views collectively showing the said sub-units of the sharpener in an imaginary "exploded" relationship;

Fig. 7 is an isometric view illustrating how the hones may be formed integral with their respective base sections if desired;

Fig. 8 is a top plan view of a modified embodiment of my invention, the major portion of the

cover being broken away to reveal parts thereof beneath;

Fig. 9 is a longitudinal section taken in the vertical plane of the line 9—9 of Fig. 8 and looking in the direction indicated by the arrows;

Fig. 10 is a transverse section taken in the plane of the line 10—10 of Fig. 9 and looking in the direction indicated by the arrows;

Fig. 11 is a fragmentary sectional view taken in the vertical plane of the line 11—11 of Fig. 9; 10 and

Figs. 12, 13, 14 and 15 are views which respectively illustrate the blade carriage support, the twisted portion of the operating rod, the blade carriage and the blade holder,—these views collectively illustrating the said sub-units of the sharpener shown in Figs. 8 to 11 in an imaginary "exploded" relationship.

Similar characters of reference refer to similar parts throughout the several views.

Referring first to that embodiment of my invention which is shown in Figs. 1 to 6 inclusive, the sharpener comprises a base 20, and if desired, a cover 21 which is removed when the sharpener is in use.

I prefer that the base shall consist of two complementary sections or halves 20a and 20b, formed from a moldable composition, such for example, as a suitable one of the several well known moldable phenolic condensation products; these base 30 halves being secured together, and held in proper alignment, by screws 22, 22 and a key 23 which is formed on one of said halves and engages a corresponding groove in the other.

Carried by the base sections 20a and 20b, re-

spectively, are the hones 24 and 25,—each of these hones preferably, but not necessarily, being in the form of an elongated body of natural or artificial stone. The hones 24 and 25 are parallel, are spaced apart horizontally, and are 40 grooved on their opposed sides to provide two spaced-apart pairs of honing surfaces 24a, 24b and 25a, 25b. In this embodiment of my invention the hone grooves or channels are preferably

V-shaped so that the honing surfaces of each of the aforesaid pairs will diverge toward the other pair of honing surfaces,—all of the honing surfaces being disposed at equal angles to a horizontal plane passing through the apices of said 50

V-shaped grooves or channels.

While the hones 24 and 25 may be secured to their respective base sections 20a and 20b in any suitable manner, I find it convenient to dovetail the lower portions of the hones as shown and to

5

20

25

30

35

40

45

50

55

embed them in the upper portions of the base sections when the latter are molded.

Formed in the opposed surfaces of the base sections 20a and 20b are semi-cylindrical grooves 5 which together constitute a cylindrical chamber 26 which extends longitudinally of the base and terminates just short of each of its ends. Cylindrical chamber 26 opens upwardly, between the hones 24 and 25, through a slot 27,—the spaced-10 apart surfaces of the base sections which define this slot being vertical and parallel.

The slot 27 may be extended somewhat beyond the ends of the cylindrical chamber 26, as indicated at 28 and 29 (Figs. 1 and 2) to accommodate maximum reciprocations of the blade carriage presently to be described. Moreover, for the same purpose and also to accommodate the abutment of the operating rod presently to be mentioned, a small chamber 30, which communicates with the cylindrical chamber 26 and slot 27, is formed in the base sections.

I now call attention to the blade carriage support 31 which occupies and operates in the cylindrical chamber 26 and slot 27 of the base. This 25 blade carriage support, which preferably is formed of one piece of metal, comprises a pair of oppositely facing channels 32, 32, and a cylindrically curved spring-web 33 which integrally joins the lower edges of the channels 32, 32.

The spring web 33 occupies the cylindrical chamber 26 of the base while channels 32, 32 embrace and bear against those parallel vertical surfaces of the base sections which define the slot 27. The upper flanges of the channels 32, 35 32, which slide upon the tops of the base sections, are horizontal, while the lower flanges of said channels are curved to bear snugly against the contiguous portions of the curved wall of cylindrical chamber 26. The pressure with which 40 spring-web 33 urges the channels 32, 32 against the walls of the slot 27 is carefully determined because, as will hereinafter be explained, it is this pressure of channels 32, 32 against the slot walls which determines the pressure with which 45 the edges of the blade to be sharpened are pressed against the honing surfaces in the operation of the sharpener.

Fixedly carried by one of the channels 32 of the blade carriage support is a pin 34, which is 50 freely received by an aperture 35 in the other channel 32. This pin 34, which bridges the space between the channel backs (and serves as the pivot for the blade carriage bell crank presently to be described) does not interfere with the function of spring-web 33 to force the channels 32, 35 32 firmly into engagement with the walls of slot 27 (see Fig. 3).

The blade carriage, indicated as a whole at 36, comprises an elongated body portion 37 which 60 consists of a metal strip formed to give it the shape of a narrow U in transverse sections,—the legs of this U being provided with oppositely turned horizontal flanges 38—38. The lower left hand corner (Fig. 5) of the carriage body member 37 is preferably cut away, as indicated at 39, to enable movement of said carriage to the extreme left hand position indicated in Fig. 2.

The right hand end (Fig. 5) of the carriage body member 37 is slotted to receive the lower 70 and shorter arm of a curved leaf spring 40, which has its upper and longer arm disposed over the member 37 with a tendency to press against the latter. The said lower and shorter arm of the leaf spring 40 is conveniently soldered in the 75 slot by which it is received. Lying between car-

riage body member 37 and the upper arm of the spring 40, and clamped to the former, and by the latter, is a bar 41 having the cross sectional shape of a shallow inverted U, this bar having an integral upturned lug 42 which extends freely through a small aperture located near the extremity of the upper arm of the leaf spring 40. A pair of spaced lugs 43, 43, turned upwardly from the right hand end (Fig. 5) of the bar 41 embrace the curved portion of the spring 40 between them, and, with previously mentioned lug 42, maintain the bar 41 in substantial alignment with carriage body member 37 and the upper arm of the said spring 40.

It will be noted that a V-shaped notch 44 is 15 cut in the lower edge of the carriage body member 37,—this notch serving to accommodate bell crank lever 45 and the previously mentioned pin 34, whereby said bell crank lever is pivoted to the channels 32, 32 of the blade carriage support 31. 20 One arm of this bell crank lever 45 lies between the spaced walls of the carriage body member 37 and is pivoted to the latter by pin 46. The other arm of said bell crank lever is pivoted by pin 47 to the bifurcated extremity of an operating rod 48.

Operating rod 48 is arranged to slide freely through a bearing in the right hand end (Fig. 2) of the base,—said bearing being formed by opposed semi-cylindrical grooves molded in the base 30 sections 20a and 20b. At its outer end rod 48 carries handle 49 and, midway between its ends, may be provided with an abutment 50. Handle 49 is rotatably mounted on rod 48. The abutment 50, in the present showing, has taken the form of a 35 partial sleeve soldered or otherwise fixed upon rod 48. The engagements of handle 49 and abutment 50, respectively, with the outer and inner surfaces of the right hand (Fig. 2) end wall of the base, determine the reciprocation limits of 40 rod 48.

The blade holder 51 comprises a bar having downturned lateral flanges 52, 52 arranged to rest on the flanges 38, 38 of the blade carriage body member 37. Projecting upwardly from the 45 upper surface of the blade holder bar are spaced studs 53, 53 which are arranged to engage in suitable correspondingly shaped holes formed in a conventional two edged safety razor blade, indicated at 54. A flange 55 is preferably turned 50 up at the left hand end (Fig. 6) of the blade holder bar to serve as a handle wherewith to manipulate the blade holder onto and off of the blade carriage previously mentioned. Flange 55 also serves as a stop when inserting the blade 55 holder into the blade carriage.

When it is intended that the sharpener of the present invention shall handle safety razor blades of a plurality of styles and makes, the sharpener will be equipped with a plurality of blade holders, 60 each of these blade holders being provided with one or more lugs, corresponding to the studs 53, 53 previously mentioned, shaped and disposed to cooperate with the openings found in the particular style or make of blade with which the 65 holder is intended to cooperate.

In using the sharpener just described, the blade to be sharpened is placed on its blade holder substantially as shown in Fig. 6. The left hand end (Fig. 5) of the blade carriage bar 41 is then lifted 70 against the pressure of spring 40 and the blade holder is slipped under said bar 41,—each edge of the razor blade occupying a position between the honing surfaces (24a, 24b and 25a, 25b) of each pair of opposed honing surfaces. The 75

sharpener is now ready to perform its function.

The handle 49 is grasped and moved to its dotted line position from the full line position shown in Figs. 1 and 2. At the commencement 5 of this movement, the bell crank lever 45 turns counterclockwise (Fig. 2) to raise the blade carriage and firmly press the blade edges into engagement with the upper honing surfaces 24a and 25a,—the pressure with which the blade edges engage the said honing surfaces being determined by the force necessary to overcome the friction between the channels 32, 32 of the blade holder support and the vertical walls of the base slot 27. When that friction is overcome, the 10 blade carriage support, blade carriage, blade holder and the blade are moved to the right (Fig. 2), each blade edge having sliding contact, in a line paralleling such edge, with one of the upper honing surfaces 24a and 25a.

On reverse reciprocating movement of the handle 49, the bell crank lever 45 turns in a clockwise direction (Fig. 2) until the blade carriage has been lowered firmly to press the blade edges against the lower honing surfaces 24b and 25b. 15 Continued pressure on the handle overcoming the friction between the blade holder support and the base, the blade edges move over the lower honing surfaces 24b and 25b, again in lines parallel to said blade edges.

The operations just described are repeated as reciprocation of the handle 49 continues,—the blade edges, during movements of the handle in opposite directions, alternately engaging the upper and lower honing surfaces which define the channels in which the blade edges move, and always yieldingly bearing against those honing surfaces with pressures determined by the friction between the base and the blade holder support 31.

In the embodiment of my invention just described, the edge forming angles at which the honing surfaces engage the razor blade are determined by the angularity of the honing surfaces to the two parallel planes, upper and lower, which the blade occupies and in which it moves when reciprocating in opposite directions.

In Fig. 7 I have illustrated how the hones, of the type of device depicted in the preceding figures, may be formed integral with the molded base sections by which said hones are carried. Fig. 7 shows but one of these molded base sections having a hone formed integral therewith. It may be assumed that the molded base section shown in the figure under discussion is formed 50 from a moldable phenolic condensation product having a considerable amount of suitable abrasive admixed with it before the performance of the molding operation. While in some cases it may be possible to confine the abrasive to the hone region of the molded base section, it is usually not practical to do so. Therefore, when I form the hones integral with their respective base sections, and incorporate abrasive material into the base sections as just explained, I prefer to line the walls of the base slot 27 with channels 55 56, the purpose of these channels being to be embraced by and to prevent that undue wear of the blade carriage support channels 32, 32 which would occur if such last mentioned channels were in direct sliding contact with base section walls having a substantial amount of abrasive embedded therein. Otherwise than as just explained a sharpener comprising base sections each having an integral hone, as depicted in Fig. 7, may be 60 identical in construction and mode of operation

with the sharpener illustrated in Figs. 1 to 6, both inclusive.

In the modified embodiment of my invention illustrated in Figs. 8 to 15 inclusive, I provide a base 60 consisting of molded complementary base sections 60a and 60b secured together and held in proper alignment by screws 61, 61 and key 62. This embodiment of the invention also may be provided with a cover 63, of any suitable material, which is preferably removed when the sharpener 10 is in use.

In this form of my invention the spaced-apart hones 64 and 65, which are preferably formed of natural or artificial stone, are held upon their respective base sections 60a and 60b by screws 66, 15 66,—it being found advantageous, in order to keep the hones in precise alignment with their respective base sections and with each other, to provide each hone on its lower surface with an integral rib 68 which engages in a correspondingly shaped slot formed in the upper surface of the base section by which such hone is carried.

The spaced-apart lateral surfaces of the hones 64 and 65 are provided with grooves or channels so that each hone presents a pair of opposed upper and lower honing surfaces,—the opposed upper and lower honing surfaces of the hone 64 being indicated at 64a and 64b, respectively, and the corresponding honing surfaces of the hone 65 being indicated at 65a and 65b, respectively.

In this embodiment of my invention it is desirable to have the upper and lower honing surfaces of each hone parallel with each other, for the reason that the blade carriage, which serves to shift a blade to be sharpened into and out of engagement with these honing surfaces, tilts laterally on its longitudinal axis, to determine the edge-forming angles between the blade to be sharpened and the honing surfaces with which its edge or edges engage in the operation of the sharpener.

The base sections 60a and 60b are conformed to provide the elongated chamber 67 which has upwardly converging side walls, as is most clearly shown in Fig. 10. Chamber 67 opens upwardly, 45 between the hones, through a slot 68. The opposed surfaces of the base sections which define base slot 68 are vertical and parallel for cooperation with the blade carriage support next to be described.

The blade carriage support, indicated as a whole at 69, comprises a single piece of sheet metal conformed to provide aligned spaced-apart rod guides 70, 70, webs 71, 71 which bear yieldingly but with substantial pressure against the walls of base slot 68, and downwardly diverging flanges 72, 72, which bear against the upwardly converging walls of base chamber 67, to prevent the escape of the said blade carriage support from the base wherein and whereon it reciprocates.

The blade carriage indicated as a whole at 73 comprises a metal strap 74, which is turned back upon itself, as indicated at 75, to provide a spring arm 76, which in turn is provided near its free end with laterally projecting lugs 77, 77. These lugs 77, 77 engage in correspondingly shaped apertures formed in a pair of spaced-apart lugs 78, 78, which are struck upwardly from a channel member 79. Channel member 79, which serves 60 65 70 as a clamp for the blade and blade holder presently to be mentioned, is urged, by spring arm 76, toward the lower or body portion of the blade carriage strap 74.

Soldered to the under surface of the lower or 75

body portion of the blade carriage strap 74 are the ends of a metal strap which has been conformed to provide a nut 80 for a four threaded screw formed by twisting the inner end portion 5 81 of an operating rod 82, which, except at its twisted portion, is of square cross section.

The twisted portion 81 of the operating rod cooperates with nut 80 and extends freely through the rod guides 70, 70 of the blade carriage support. Turning of the rod 82 about its longitudinal axis is prevented by a bearing 83, of sheet metal, which slidingly embraces the rod 82 at the right hand end (Fig. 2) of the base. This bearing 83 is held snugly in recesses formed in those 10 opposed surfaces of the base sections between which said bearing is disposed (Fig. 11). At its outer end rod 82 is provided with the operating handle 84, the latter being rotatable on the former.

20 The blade holder of the sharpener under discussion comprises channel member 85, the flanges of which are arranged to embrace the lateral edges of the lower or body portion of the blade carriage strap 74. The blade holder channel is 25 provided at its left hand end (Fig. 15) with an upturned flange 86 to serve as a handle for manipulating the blade holder into and out of the blade carriage. Flange 86 also serves as a stop when inserting the holder into the carriage. The 30 blade holder channel is also provided on its upper surface with a circular stud 87 and a generally A-shaped stud 88 for the reception by the apertures formed in a familiar style of safety razor blade, indicated at 89, which has but one sharpened edge.

35 In order to sharpen the blade 89, it is placed on blade holder channel 85, as indicated in Fig. 15, and the blade holder, with the blade thereon, is slipped under the blade carriage channel 79, with the flanges of the blade holder channel embracing the lateral edges of the lower or body portion 40 of the blade carriage strap member 74.

The proper insertion of the blade holder into the blade carriage causes the sharpened edge of 45 the blade 89 to lie in the channel formed by the upper and lower honing surfaces 64a and 64b of the hone 64. It will be understood, of course, that the blade 89 might be of a type having two sharpened edges, in which event the second of 50 its sharpened edges would lie in the channel of the hone 65 for cooperation with the upper and lower honing surfaces 65a and 65b of said hone.

55 The blade is sharpened by reciprocating the handle 84 from one to the other of its dotted line positions, indicated in Fig. 8.

It may be assumed, for the purpose of drawing description, that the handle 84 is being reciprocated from its full line position to the left hand one of its dotted line positions indicated 60 in Fig. 8. With the handle so moving the blade carriage is tilted to the position indicated in Fig. 10, due to the engagement of the nut 80 with the threaded portion 81 of the rod 82, and the sharpened edge of the razor blade bears 65 against the lower honing surfaces 64b with the pressure determined by the force necessary to cause the blade carriage support 69, and parts carried thereby, to slide on and relative to the base, despite its frictional engagement with the 70 latter.

When the handle 74 has moved to the right (Fig. 8), the engagement of the nut 80 with the twisted portion 81 of the operating rod tilts the 75 blade carriage through a few degrees, in a clockwise direction from the position shown in Fig. 10,

to cause the sharpened edge of the blade to leave the honing surface 64b and engage the honing surface 64a with a pressure that can be determined by the sliding friction between the blade carriage support 69 and the base.

5 As the handle 84 continues to be reciprocated in opposite directions, the sharpened edge of the blade alternately engages the honing surfaces 64a and 64b, and while engaging such honing surfaces moves with respect thereto in a line parallel to such edge. The edge-forming angle of the blade and the honing surface which it is engaging in either of its reciprocatory movements, is determined by the tilt of the blade carriage with respect to the planes of the honing surfaces which, in the present embodiment of my invention, are all horizontal.

Having thus illustrated and described my invention in two preferred embodiments thereof, I do not limit myself to the details of construction 20 herein described and illustrated, but, to the contrary, desire to secure all embodiments of my invention falling within the scope of the appended claims.

What I claim as new and desire to secure by 25 Letters Patent of the United States is:

1. In a razor blade sharpener, a base, a pair of opposed honing surfaces defining a channel, a blade carriage mounted for reciprocation on the base and arranged to support and move a blade with an edge in said channel, means for reciprocating the carriage, and carriage shifting mechanism, responsive to movements of the aforesaid reciprocating means, functioning to effect a complete lateral shift of the carriage at 35 right angles to the direction of its reciprocation to place the edge of a blade carried by said carriage in contact with said honing surfaces, alternately, when the reciprocating means is actuated to move the carriage in opposite directions, each lateral shift of the carriage, as aforesaid, accomplishing a movement of its axis laterally.

2. A razor blade sharpener comprising a base, a pair of parallel spaced-apart hones supported by the base, razor blade edge receiving channels formed in the sides of said hones which are presented to each other, a blade carriage operating between said hones and arranged to carry a blade with an edge thereof in each of said channels, a carriage support having frictional sliding engagement with the base, a bell crank pivoted to said carriage support and having one arm thereof pivoted to the blade carriage, and an operating rod to which the other end of said bell crank is pivoted, substantially as described.

3. In a razor blade sharpener, a base, a pair of parallel spaced-apart hones supported by the base, razor blade edge receiving channels formed in the sides of said hones which face each other, a blade carriage operating between said hones, a blade carriage support for sliding frictional engagement with the base, said blade carriage support providing spaced-apart guides for an operating rod, an operating rod having a threaded portion occupying said guides, and a nut carried by the blade carriage located between said guides and cooperating with the threaded portion of the operating rod to tilt the blade carriage about said rod as an axis preparatory to reciprocating movements of the carriage and carriage support accomplished by movements of said operating rod.

4. In a razor blade sharpener, the combination of a base, a pair of honing surfaces carried by 75

the base and defining a blade edge receiving channel, a blade carriage reciprocably mounted on the base, means for reciprocating the blade carriage, and carriage shifting mechanism responsive to actuation of the reciprocating means arranged and adapted to cause an edge of the blade carried by said carriage to engage one and then the other of said honing surfaces as the carriage is reciprocated, said carriage shifting mechanism comprising a blade carriage support having frictional sliding engagement with the base and a lever pivoted to said blade carriage support constituting an operating connection between the blade carriage and the carriage reciprocating means.

5. In a razor blade sharpener, a base, a blade carriage, a blade carriage support having frictional sliding engagement with the base, said blade carriage being articulated with the blade carriage support for movement relatively to said blade carriage support, a pair of honing surfaces stationarily carried by the base and defining a channel for the reception of an edge of a razor blade carried by said blade carriage, and operating devices, connected with said blade carriage and blade carriage support, arranged and adapted when actuated simultaneously to reciprocate said blade carriage and said blade carriage support, and shift the blade carriage relatively to the blade carriage support, prior to each reversal of reciprocatory movement, to move an edge of the blade away from one of said honing surfaces and place and hold said edge against the other of said honing surfaces with a honing pressure determined by that friction, between the base and the blade carriage support, which must be overcome before the blade carriage support and blade carriage are reciprocated.

40. 6. In a razor blade sharpener, a base, an elongated slot in said base, an expansible blade carriage support having portions extending into said slot and bearing against the walls thereof frictionally to oppose relative sliding movement between the base and said blade carriage support, a blade carriage mounted on and shiftable with respect to said blade carriage support, a pair of honing surfaces stationarily carried by the base and defining a channel for the reception of an edge of a razor blade mounted on said blade carriage, and operating devices connected with said blade carriage support and said blade carriage to reciprocate the same and shift said blade carriage relative to said blade carriage support prior to each reciprocatory movement to effect the movement of the blade edge from one to the other of said honing surfaces.

60. 7. In a razor blade sharpener, a base, an elongated slot in said base, a chamber in the base with which said slot communicates, a blade carriage support which comprises a pair of friction members bearing against the walls of said slot and an expansible member occupying said base chamber and tending to press said friction members against the walls of said slot, a blade carriage mounted on and shiftable with respect to said blade carriage support, a pair of honing surfaces stationarily carried by the base and defining a channel for the reception of an edge of a razor blade mounted on said blade carriage, and operating devices connected with said blade carriage support and said blade carriage to reciprocate said last mentioned elements and shift said blade carriage relative to said blade carriage support prior to each reciprocatory movement to

effect the movement of the blade edge from one to the other of said honing surfaces.

8. In a razor blade sharpener, a base, an elongated slot in the base, a chamber in the base with which said slot communicates, a blade carriage support having a pair of spaced friction members extending into said slot and provided with offset terminal portions occupying said chamber, a spring-web connecting said friction members and tending to press the same against the walls of said slot, a blade carriage mounted on and shiftable with respect to said blade carriage support, a pair of honing surfaces stationarily carried by the base and defining a channel for the reception of an edge of a razor blade mounted on said blade carriage, and operating devices connected with said blade carriage support and said blade carriage to reciprocate the elements last mentioned and shift said blade carriage relative to said blade carriage support, prior to each reciprocatory movement, to effect the movement of the blade edge from one to the other of said honing surfaces.

9. In a razor blade sharpener, a base, an elongated slot in the base, a blade carriage support comprising a pair of spaced friction members having corresponding edges joined by a spaced pair of substantially cylindrical spring-webs, said friction members occupying said slot and being pressed against the walls of the slot by said spring-webs, a non-rotatable threaded operating rod occupying said spring-webs and bridging the space between them, a blade carriage disposed above said blade carriage support and provided with a nut cooperating with the threaded rod, said nut occupying the space between the substantially cylindrical spring-webs, and a pair of spaced-apart honing surfaces stationarily carried by the base and adapted alternately to be engaged by an edge of a blade carried by said blade carriage when the latter is tilted, by cooperation of said nut and threaded rod, prior to each reciprocation of said blade carriage and said blade carriage support.

40. 10. In a razor blade sharpener, the combination of a base, a pair of honing surfaces carried by the base and defining a substantially V-shaped channel, a blade carriage reciprocably mounted on the base, means for reciprocating the blade carriage, and carriage shifting mechanism, responsive to actuation of the reciprocating means, arranged and adapted to cause an edge of the blade carried by said carriage to engage first one and then the other of said honing surfaces as the carriage is reciprocated, said carriage shifting mechanism comprising a blade carriage support having frictional sliding engagement with the base and a lever pivoted to said blade carriage support constituting an operating connection between the blade carriage and the carriage reciprocating means.

60. 11. In a razor blade sharpener, a blade carriage comprising an elongated body member, a leaf spring having one end thereof attached to one end of said body member, the other end of the leaf spring overlying said body member, a clamping bar which is of inverted U shape in transverse cross section, said clamping bar being carried by the free end of said leaf spring and being by the latter pressed toward the upper surface of said body member, and a blade holder of inverted U shape in transverse cross section adapted to lie between said clamping bar and the body member, and to embrace said body member, and projections on the upper surface of the blade holder

5

55

60

65

70

75

adapted to project through apertures in a razor blade, said projections being received by the U-shaped clamping bar when the blade holder is positioned between the clamping bar and the body member.

12. In a razor blade sharpener, a blade carriage comprising a body member provided at one end with an integral spring arm turned back to overlie said body member, a clamping bar of inverted U shape in transverse cross section pivoted to the free end of said spring arm and being by the latter urged toward said body member, a blade holder of inverted U shape in transverse cross section adapted to lie between the body member and the clamping bar and to embrace the body member, and projections on the upper surface of the blade holder adapted to project through apertures in a razor blade disposed on said holder, said projections being received in

10 the channel of the clamping bar when the blade holder is disposed between the clamping bar and the body member and is embracing the latter.

15 13. In a razor blade sharpener, a blade carriage comprising a body member, a curved leaf spring extending from one end of the body member and being turned to overlie said body member, a clamping bar of inverted U shape in transverse cross section disposed over said body member and carried by that portion of the leaf spring which

20 overlies the body member, said leaf spring tending to urge said clamping bar toward said body member, and a blade holder of inverted U shape in transverse cross section adapted to embrace the body member and to lie between the latter and the clamping bar, and projections carried by the upper surface of the blade holder adapted to extend through apertures in a razor blade, said projections being received in the channel of the clamping bar when the blade holder is embracing the body member and is clamped to the latter by means of the clamping bar and its associated leaf spring.

14. In a razor blade sharpener, a base, a blade carriage, a blade carriage support having frictional sliding engagement with the base, a pair of honing surfaces stationarily carried by the base and defining a channel for the reception of a razor blade carried by said blade carriage, and operating devices, connected with said blade carriage and said blade carriage support, arranged and adapted when actuated simultaneously to reciprocate said blade carriage and said blade carriage support and shift the blade carriage relatively to the blade carriage support, prior to each reversal of reciprocatory movement, to move an edge of the blade away from one of said honing surfaces and place and hold said edge against the other of said honing surfaces with a honing pressure determined by that friction, between the base and the blade carriage support, which must be overcome before the blade carriage support and blade carriage are reciprocated, the aforesaid operating devices comprising an actuating rod, mounted for reciprocation relatively to the base,

and a lever, said lever being pivotally connected with each of the rod, blade carriage support, and blade carriage.

15. In a razor blade sharpener, a base, a blade carriage, a blade carriage support having frictional sliding engagement with the base, a pair of honing surfaces stationarily carried by the base and defining a channel for the reception of a razor blade carried by said blade carriage, and operating devices, connected with said blade carriage and said blade carriage support, arranged and adapted when actuated simultaneously to reciprocate said blade carriage and said blade carriage support and laterally tilt the blade carriage relatively to the blade carriage support, prior to each reversal of reciprocatory movement, to move an edge of the blade away from one of said honing surfaces and place and hold said edge against the other of said honing surfaces with a honing pressure determined by that friction, between the base and the blade carriage support, which must be overcome before the blade carriage support and blade carriage are reciprocated, the aforesaid operating devices comprising an actuating rod mounted for reciprocation relatively to the base, means for preventing rotation of said actuating rod, a nut carried by the blade carriage, and a threaded element carried by the actuating rod and cooperating with said nut.

16. In a razor blade sharpener, a base, a blade carriage support mounted on and reciprocable with respect to the base, a blade carriage mounted on said blade carriage support for movement relative to the latter, an operating member connected with said blade carriage support and said blade carriage, said operating member being capable of alternate movements in opposite directions, instrumentalities cooperating with said blade carriage support, blade carriage and operating member and adapted, on reversal of movement of such operating member, to effect, firstly, relative movement between blade carriage and blade carriage support, and, secondly, movement in unison of blade carriage support and blade carriage relatively to the base, a pair of honing surfaces, stationarily carried by the base and defining a channel for the reception of an edge of a razor blade carried by said blade carriage, one of said honing surfaces being engaged by said blade edge during movements in unison of the blade carriage and blade carriage support in one direction, and the other of said honing surfaces being engaged by said blade edge during movements in unison of the blade carriage and blade carriage support in the opposite direction, and resilient friction members acting between the base and blade carriage support to prevent reversals of movement of blade carriage support with respect to the base until a preceding movement of the blade carriage with respect to the blade carriage support has shifted the blade edge from one to the other of said honing surfaces.

WILLIAM LUXMORE.
